(57) **CLAIM**The ornamental design for a remote controller for bidet, as
shown and described.

DESCRIPTION

FIG. 1 is a perspective view of a remote controller for bidet,
showing my new design;

FIG. 2 is a front view thereof;

FIG. 3 is a rear view thereof;

FIG. 4 is a left-side view thereof;

FIG. 5 is a right-side view thereof;

FIG. 6 is a top plan view thereof; and,

FIG. 7 is a bottom plan view thereof.

In figures the broken lines are for the purpose of illustrating
environment only and form no part of the claimed design.**1 Claim, 7 Drawing Sheets**(56)
